UNITED STATES PATENT OFFICE.

CHARLES J. FOSTER, OF VAN WERT, OHIO.

DEVICE FOR CURING INGROWING TOE-NAILS.

No. 884,376.

Specification of Letters Patent. Patented April 14, 1908.

Application filed September 19, 1907. Serial No. 393,664.

To all whom it may concern:

Be it known that I, CHARLES J. FOSTER, a citizen of the United States, residing at Van Wert, in the county of Van Wert and State 5 of Ohio, have invented certain new and useful Improvements in Devices for Curing Ingrowing Toe-Nails, of which the following is a specification.

The present invention relates to mechanical means for remedying ingrowing toe nails, 10 the same consisting of a device for effecting lateral constriction of the nail so as to relieve the painful pressure of the edge portions upon the adjacent flesh.

15 The device consists of clips adapted to be fitted to opposite edge portions of the ingrowing nail and a yielding connection joining said clips and constantly exerting a pressure to draw the same together so as to constrict 20 the nail and relieve the soreness incident to the nail and the abnormal pressure of the edges of the nail upon the adjacent flesh of the digit.

25 For a full understanding of the invention and the merits thereof and also to acquire a knowledge of the details of construction and the means for effecting the result, reference is to be had to the following description and accompanying drawings.

30 While the invention may be adapted to different forms and conditions by changes in the structure and minor details without departing from the spirit or essential features thereof, still the preferred embodiment is shown in the accompanying drawings, in 35 which:

Figure 1 is a perspective view of a digit or toe, showing the application of the invention. Fig. 2 is a transverse section on the line x—x of Fig. 1. Fig. 3 is a perspective view of the

40 device.

Corresponding and like parts are referred to in the following description and indicated in all the views of the drawings by the same reference characters.

45 The appliance consists of complementary 50 clips 1 and a yielding connection 2. The clips 1 may be of any construction, the purpose being to provide means for making positive engagement with opposite longitudinal edge portions of the nail. The yielding connection 2 may be of any type, the purpose being to draw the clips 1 together by a constant force, so as to gradually constrict the nail and withdraw its edge portions from engagement with the adjacent portions of the

flesh, so as to relieve the pain and soreness incident to ingrowing nail. As shown, the yielding connection 2 consists of an elastic band. The clips 1 have hooks 3 which engage opposite end portions of the elastic band and prevent displacement thereof. Each of the clips consists of a strip of sheet metal having its end portions rebent upon opposite sides to form the nail engaging hooks 4 and the hooks 3 for receiving the yielding connection 2.

For the successful treatment of ingrowing nail, a V-shaped notch 5 is formed in the outer end of the nail 6 and the clips 1 are placed in position with the hooks 4 engaging under opposite edge portions of said nail, the clips resting upon the nail and their hooked ends 3 being connected by the elastic bands 2, the tension of which is such as to exert a constant and gradual force to draw the clips 75 together and produce constriction of the nail 6, the V-shaped notch 5 admitting of the separated portions of the nail being drawn together, whereby the opposite longitudinal edges are withdrawn from engagement with 80 the adjacent portions of the flesh which produces the pain and soreness.

Having thus described the invention, what is claimed as new is:

1. Means for relieving ingrowing nail, the 85 same consisting of complementary clips each having integral hooks at opposite ends, the hooks at one end of the clips being adapted to engage and embrace edge portions of the nail, and a yielding connection fitted to the 90 hooks at the opposite ends of the clips to constantly draw the clips together.

2. Means for relieving ingrowing nail, the 95 same consisting of complementary clips, each clip formed of a strip of sheet metal having end portions rebent in opposite directions to form hooks, the hooks at one end of the clips being designed to engage beneath the nail and over the edges thereof, and the other hooks projecting outward, and an elastic 100 connection fitted to the last mentioned hooks to draw the clips together and effect constriction of the nail.

In testimony whereof I affix my signature in presence of two witnesses.

CHARLES J. FOSTER. [L. S.]

Witnesses:

CLEM V. HOKE,
BLANCHE TANQUARY.
